[57] CLAIM

The ornamental design for a foam handled dog leash, as shown.

DESCRIPTION

FIG. 1 is a front elevational view of a foam handled dog leash, showing my new design, the rear view being a mirror image thereof;

FIG. 2 is a left side elevational view, the right side being a mirror image thereof;

FIG. 3 is a top plan view of the handle portion; and,
FIG. 4 is an enlarged perspective view of the handle portion.
